UNITED STATES PATENT OFFICE.

ALEXANDER BOYNTON, OF SAN ANTONIO, TEXAS.

POLISHED-ROD ROTOR.

Application filed June 29, 1926. Serial No. 119,508.

This invention relates to polished rod rotors of the chain actuated type and an important object is the provision of simple and reliable means whereby a polished rod, 5 the sucker rods and the fluid lifting unit connected thereto, may be turned in a clockwise direction to avoid the formation of squirt grooves in the working barrel and the fluid lifting unit and at the same time 10 to exert an intermittent tightening effect on the rods at the joints thereof, all of which is intended to avoid frequent interruptions of the pumping of the well.

Another important feature is the provision 15 of means whereby the rotor is rendered temporarily inoperative when the twist in the rods exceeds a predetermined point as a result of the sticking of the fluid lifting unit, such as the cups or plunger.

20 A further object is to provide a polished rod rotor of the character specified which may be applied without the exercise of unusual skill and without substantial alteration of parts already in use.

25 A further object is to provide a polished-rod rotor which in addition to giving visual evidence of normal operation will give an audible signal so that in the event of improper operation proper adjustment or repair may be quickly made.

Other objects and advantages will be apparent during the course of the following description.

In the accompanying drawings forming 35 a part of this application and in which like numerals are employed to designate like parts throughout the same,

Figure 1 is a perspective of the improved rotor applied;

40 Figure 2 is a front elevation of the rotor, a portion of the attaching means thereof being broken away;

Figure 3 is a fragmentary group perspective illustrating a motion transmitting mechanism embodied in the invention;

45 Figure 4 is a side elevation illustrating a slight modification of the invention;

Figure 5 is a front elevation of the rotor shown in Figure 4, the view illustrating the 50 attaching means.

In the drawing, the numeral 5 designates a polished rod which is, of course, connected to the sucker rods in the usual manner.

As well known the sucker rods support a 55 fluid lifting unit such as a series of cups or

a plunger, both of which operate in a working barrel. Figure 1 illustrates that the polished rod is extended through a trunnion 6 of special design and that the trunnion is provided with a trunnion screw 60 9 adapted to be tightly engaged with the polished rod preparatory to and during the application of the improved rotor so that the polished rod and the parts connected thereto may not drop. Of course, when the 65 rotor has been applied the screw 9 must be loosened to allow of the free turning of the polished rod under the influence of the rotor.

Figure 1 clearly illustrates that the 70 branches of the trunnion 6 are extended beyond the sides of the beam and are provided with grooved enlargements 10 received within the eyes 11 of attaching bolts 12. The attaching bolts 12 are in turn 75 threaded into the upper terminal portions of a U-shaped stirrup or frame 14 and at this point it is noted that the stirrup may be adjusted by turning of one or both of the eye bolts 12 as will be obvious. 80

Attention is now invited to Figure 2 which illustrates that a rotor element is mounted between the sides of the U-shaped stirrup 14 and comprises members 16 and 17, the member 16 being fixed to the polished 85 rod by set screws 18 or other suitable fastening devices. The opposed ends of the sections 16 and 17 are provided with ratchet teeth so that when the section 17 is turned in a clockwise direction similar movement 90 will be imparted to the polished rod. The teeth of the section 17 are urged into engagement with the teeth of the section 16 through the medium of a spring confined 95 within a shell 19. Of course, the spring contracts each time the movable section 17 partakes of a backward or a counter clockwise movement preparatory to again turning the polished rod and associated parts.

In carrying out the invention the member 100 17 is provided with a radial arm consisting of telescopic sections 20 and 21, the section 21 preferably being integral with the member 17, while the section 20 slidably receives the section 21 and is provided with a more 105 or less cylindrical terminal 22.

The cylindrical terminal 22 which, for the purpose of lightness and providing for lubrication may be hollow, is slidably received in the transversely curved crank 23 110

of a sprocket wheel 24. The sprocket wheel is mounted on a shaft 26 having a sectional attaching member 27, which as illustrated in Figure 2 is mounted upon the intermediate portion of the member 16. The intermediate portion of the member 16 is preferably grooved to define a pair of annular shoulders between which the sectional attaching member is confined. The outer portion of the shaft 26 is extended through an opening in the adjacent side of the stirrup and is thereby braced.

The crank 23 describes somewhat more than a semi-circle in cross section and consequently holds the cylindrical terminal 22 therein, but at the same time permits the cylindrical terminal to partake of the necessary movement in the crank as a result of the rocking of the crank. When the crank 23 is rocked the distance between it and the axis of the rotor will vary at different positions of the crank and to provide for this the section 20 is allowed to slide longitudinally on the section 21 without at any time breaking the driving connection between the crank and the rotor member 17. Also the cylindrical terminal is capable of, and actually does partake of a limited turning within the transversely curved actuating crank 23.

Attention is now invited to Figure 1 which clearly illustrates that the sprocket wheel or segment is engaged by the intermediate portion of a sprocket chain 29 and that the ends of the sprocket chain are anchored to sprocket wheels 30 secured by bolts 32 to an arm 33. The arm 33 is in turn connected to the beam as indicated at 34 so that the terminals of the arm extend substantially the same distance at both sides of the plane of the polished rod. This results in uniform movement of the chain in both directions. Figure 1 further illustrates that the bolts 32 which support the sprocket wheels are adjustable in elongated slots in the arm 33 so that the sprocket wheels may be adjusted to vary the turning of the segment 24. It is believed to be obvious that an increase in the turning of the segment 24 may be accomplished by moving the sprocket wheels 30 to the extreme ends of the arm and that a reduction in the turning of the segment 24 may be accomplished by moving the anchoring sprocket wheels 30 in toward each other.

The sprocket wheels constitute a simple and effective anchoring means for the ends of the chain and by turning the same in the proper direction and then tightening the bolts 32 slack in the chain may be taken out. It is thus seen, that the sprocket wheels not only constitute an anchoring means for the ends of the chain, but also provide a simple adjusting means for the chain.

Attention is invited to Figures 1 and 2 which illustrate that a polished rod clamp 7 is mounted on the polished rod immediately

above the rotor unit and transmits the load of the polished rod and the column of fluid through the rotor section 16 to the stirrup 14. The load thus transmitted to the stirrup 14 is in turn transmitted through the trunnion 6 to the beam.

One of the most important features of the invention resides in the means by which excessive back strain in the rods as the result of sticking of the lifting unit such as a series of cups or a plunger is relieved. It will be seen, that the rotor section 16 is mounted in a shallow recess in the bight portion of the stirrup 14 and that this rotor section must turn in a clockwise direction in this shallow recess under the influence of the section 16. When the section 16 is thus turned in a clockwise direction, it will normally remain in this turned position until another clockwise movement is imparted to it. The frictional contact between the lower end of the section 16 and the bottom wall of the recess into which the section 16 extends, is sufficient to normally hold the rods against back turning under the slight twisting tendency which may normally be present.

However, should the lifting unit, such as a series of cups or a plunger, stick the continued operation of the rotor will cause a back strain to be built up in the rods and when this back strain exceeds a predetermined point the friction between the section 16 and the stirrup 14 will be overcome and the section 16 will partake of a counterclockwise turning movement during a similar movement of the section 17. In other words, during the return of the section 17 to a new driving position the section 16 will move with it provided, of course, the back strain in the rods is sufficient to overcome the friction between the parts 16 and 14.

In the form of invention illustrated in Figures 4 and 5, that part of the rotor which is mounted on the polished rod 5 consists of coating members 60 and 61, the member 60 being locked to the polished rod by set screws 62 or other suitable fastening devices.

Figure 5 clearly illustrates that the opposed ends of the members 60 and 61 are provided with coating ratchet teeth by means of which turning of the member 61 in a clockwise direction results in similar movement of the member 60. However, during the return of the member 61 to an operative position or more specifically during the movement of the member 61 in a counterclockwise direction the teeth of the same will ride over the teeth of the member 60 so that no turning of the member 60 results.

The member 61 is urged into engagement with the member 60 by means of a coil spring confined within a shell 63. The member 60 is extended through the member

61 and the shell and a polished rod clamp 64 of conventional or other design is connected to the polished rod immediately above and rests upon the upper terminal of the member 60 whereby the weight of the rods etc. is transmitted through the polished rod clamp, the member 60 and the washer confined within a cup 66 to the polished rod trunnion 67. The polished rod trunnion is in turn mounted on the beam 68.

The transmission of the load to the beam as described and the mounting of the member 60 on the washer within the cup 60 makes it possible for excessive back strain in the rods as a result of sticking of the cups or the like to be relieved. In explaining this point, it is pointed out that in the normal operation of the rotor the member 60 will turn only in a clockwise direction under the influence of the member 61. During the return of the member 61 in a counterclockwise direction the member 60 will partake of no turning but will remain in a relatively fixed position. However, should the cups stick, back strain will be built up in the rods with the result that the friction between the member 60 and the washer within the cup is overcome and the member 60 will move in a counterclockwise direction at the time the member 60 partakes of this movement.

In view of this, twisting of the rods to the breaking point is avoided. When the cups are freed the back strain on the rods is, of course, relieved and the rotor will again function in a normal manner so that each time the rods move downwardly they will also be moved in a clockwise direction to bring about uniform wear on the cups or plunger, as the case may be, and the working barrel and at the same time to tighten the rods at the joints thereof, all of which is intended to overcome the need of frequently interrupting the pumping operation and pulling the rods.

Figure 5 illustrates that the member 61 is provided with a radial arm consisting of inner and outer telescoping sections 70 and 71, the section 70 being preferably formed integral with the member 61 while the section 71 is slidably mounted on the section 70 and has a more or less cylindrical terminal portion 72 received within the transversely curved upper portion 74 of a crank 75. The upper portion 74 describes somewhat more than a semi-circle in cross section and therefore holds the cylindrical terminal 72 in place, but at the same time permits the member 72 to partake of the necessary sliding and turning movement therein. Figure 5 clearly illustrates that as the crank 75 approaches its extreme positions the terminal 72 will move toward the upper end of the crank and will also be turned therein. It is a simple matter to lubricate the contacting

surfaces of the members 72 and 74 and other parts of the rotor which require occasional lubrication.

The crank 75 is mounted on an attaching shaft 80, which as shown in Figure 5, is connected to one of the branches of the trunnion 67 and a sprocket wheel 81 is formed integral with or is otherwise rigidly connected to the hub of the crank so that when the sprocket wheel is rocked similar movement will be imparted to the crank.

Attention is now invited to Figure 4 which illustrates that the wheel 81 is engaged by the intermediate portion of a sprocket chain 83, the terminals of which are adjustably connected to an arm 84 by anchoring devices 85 and 86, one or both of which may be in the nature of sprocket wheels. In the illustrated embodiment of the invention the anchoring device 86 is in the nature of a sprocket wheel while the anchoring device 85 is in the nature of a clip and both of these parts may be attached to the arm 84 by fastening bolts 89. The fastening bolts are in turn extended through elongated slots in the arm 84 so that the ends of the chain may be conveniently adjusted to vary the action of the rotor. A coil spring 87 may be interposed between one end of the chain and one of the anchoring devices and functions to tension the chain.

It is noted that when it is desired to tighten the chain it is merely necessary to temporarily loosen the wheel 86 and turn the same in a counterclockwise direction and then tighten the wheel so that loosening of the chain is prevented. With reference to the foregoing description taken in connection with the accompanying drawing, it will be apparent that a polished rod rotor constructed in accordance with this invention may be easily applied without substantially altering the construction of existing parts and without departing from established practices, both of these features having been considered with a view of rendering the device acceptable to the trade. As previously stated, the employment of the rotor will bring about uniform wear on the cups and will avoid squirt grooves or jets whereby cutting of the oil or loss of production is overcome.

Having thus described the invention, what is claimed is:

1. A polished rod rotor comprising a rod turning member having a radial arm consisting of a pair of telescopic sections, one of which is provided with a driven terminal portion, and an actuator slidably and rotatably receiving said driven terminal portion.

2. A polished rod rotor comprising a rotor unit having means whereby the same may be attached to a polished rod, a support cooperating with the rotor unit in the forma-

tion of a holding means, said rotor unit having an arm consisting of a pair of telescopic sections, one of which is provided with a head, and an actuator having sliding connection with said head.

3. A polished rod rotor comprising a rotor unit having means whereby the same may be attached to a polished rod, and having an arm consisting of a pair of telescopic sections, one of which is provided with a head, and an actuator having sliding connection with said head, said head being rotatable in said actuator.

10 4. A polished rod rotor comprising a rotor unit having means whereby the same may be attached to a polished rod, and having an arm consisting of sections, one of which is provided with a head, an actuator having sliding connection with said head, said head being rotatable in said actuator, and an actuator support having means whereby the same is connected to said rotor unit.

25 5. A polished rod rotor comprising a rotor unit having means whereby the same may be attached to a polished rod, and having an arm consisting of a pair of telescopic sections, one of which is provided with a head, an actuator having sliding connection with said head, an actuator support having means whereby the same is connected to said rotor unit, a segment having connection with said actuator, and a driving chain having connection with said segment.

30 6. A polished rod rotor comprising a rotor unit having means whereby the same may be attached to a polished rod, a support cooperating with the rotor unit in the formation of a holding means, said rotor unit having an arm provided with a head, an actuator having sliding connection with said head, said head being rotatable in said actuator, an actuator support having means whereby the same is connected to said rotor unit, a segment having connection with said actuator, a driving chain having connection with said segment, and an anchoring member for said chain.

40 7. A polished rod rotor comprising a rotor unit having means whereby the same may be attached to a polished rod, and having an arm consisting of a pair of telescopic sections, one of which is provided with a head, an actuator having connection with said head, a segment having connection with said actuator, a driving chain having connection with said segment, an anchoring member for the ends of said chain, and means whereby said anchoring member may be connected to the beam of a pumping jack.

55 8. A polished rod rotor comprising a rotor unit having means whereby the same may be attached to a polished rod, and having an arm consisting of a pair of sections, an actu-

50 ator having sliding connection with one of said sections, an actuator support, a segment having connection with said actuator, and driving member having connection with said segment.

70 9. A polished rod rotor comprising a rotor assembly having means whereby the same may be mounted on a polished rod and being provided with a radial arm, an actuator having direct connection with said arm, and a shaft supporting said actuator and adapted for attachment to a polished rod trunnion.

75 10. A polished rod rotor comprising a rotor assembly having means whereby the same may be mounted on a polished rod and being provided with a radial arm, an actuator having connection with said arm, a shaft supporting said actuator and adapted for attachment to a polished rod trunnion, a sprocket wheel having connection with said actuator, and a driving chain for said wheel.

80 11. A polished rod rotor comprising a rotor assembly having means whereby the same may be mounted on a polished rod and being provided with an arm, an actuator having connection with said arm, a sprocket wheel having connection with said actuator, a driving chain for said wheel, and means for adjustably anchoring the ends of the chain.

85 90 12. A polished rod rotor comprising a rotor assembly having means whereby the same may be mounted on a polished rod and being provided with an arm, an actuator having connection with said arm, a shaft supporting said actuator and adapted for attachment to a polished rod trunnion, a sprocket wheel having connection with said actuator, and a driving chain for said wheel, there being means whereby the chain may be tensioned.

95 13. A polished rod rotor comprising a rotor assembly, a drive wheel for said rotor assembly, a chain having connection with said wheel, anchoring devices for the ends of said chain, an arm adjustably supporting said anchoring devices, and means whereby the arm may be connected to the beam of a pumping jack.

100 14. A polished rod rotor comprising a rotor assembly, a drive wheel for said rotor assembly, a chain having connection with said wheel, anchoring devices for the ends of said chain, an arm adjustably supporting said anchoring devices, one of said anchoring devices being in the form of a sprocket wheel.

105 125 15. A polished rod rotor comprising a rotor assembly, an arcuately movable actuator movable about a horizontal axis and having a power transmitting member, and a flexible driving means for said member.

In testimony whereof I affix my signature.

ALEXANDER BOYNTON.
